UNITED STATES PATENT OFFICE

EMMETT F. KENNEDY, OF CLEVELAND, OHIO, ASSIGNOR TO THE CLEVELAND COOPERATIVE STOVE COMPANY, OF CLEVELAND, OHIO, A CORPORATION OF OHIO

STOVE CONSTRUCTION

Application filed June 5, 1928. Serial No. 282,915.

This invention relates to stove constructions and has for its primary object the provision of a new and novel manner of forming connections between the frame of the stove and the side panels and top plate in such a manner that the connecting means is invisible from outside the stove, thereby producing an appearance which is pleasing to the eye.

Another object of the present invention is to provide an improved connection between the front frame of the stove and the side panels and top plate, which comprises the provision of interengaging portions between the front frame, side panels and top plate which are held in operative engagement by clamping means secured within the stove structure.

With the objects above indicated and other objects hereinafter explained in view, the invention consists of the construction and combination of elements hereinafter described and claimed.

Referring to the drawings, Fig. 1 is a front plan view of the frame of a stove embodying the present invention,

Figure 2 is a rear view of the front frame.

Figure 3 is an enlarged fragmentary view of a corner of the front frame showing the manner of connecting side panels and top plate to the frame.

Figure 4 is a fragmentary cross sectional view taken on line 4—4 of Fig. 3.

Figure 5 is a perspective view of the clamping means.

Figure 6 is a modification of the securing means shown in Figure 4, and

Figure 7 is a still further modification of the clamping means shown in Figure 4.

In the drawings, 10 represents the front frame of a stove provided with door openings 11 and 12, a portion of the door 13 being shown in Fig. 1, which is customarily pivotally connected to the front frame member 10 in the usual manner.

The front frame member 10 is provided adjacent the outer edges with rearwardly extending channel shaped portions 14 forming grooves 15. These channel shaped portions 14 may extend entirely around the

frame 10, as shown in Fig. 2, or the channel shaped portion 14 may be omitted along the lower edge of the front frame 10, in which case the bottom of the stove is formed in the usual manner.

In constructing stoves at the present time it is the general trend to avoid any obstructions or any projections upon the outer surfaces of the stove, principally due to the fact that the outer surfaces of the stoves have enameled surfaces and the omission of the obstructions or projections presents a much more pleasing effect to the eye. Furthermore, it is desirable to secure or connect the front frame, the side panels, top plate and back of the stove construction upon the interior of the stove, thereby eliminating the use of bolts which, if brought into contact with the enameled surfaces, would mar and crack the enamel. The forming of the connection within the stove is not new in the art and applicant's invention, therefore, lies in the formation of a special connection between the front frame 10 and the side panels and top plate of the stove structure.

As illustrated in the drawings, the stove construction comprises side panels 16 which are provided with portions 17 extending longitudinally thereof, of substantially Z-shape in cross section, and these Z-shaped portions are adapted to cooperate with the free leg and bottom surface of the channel shaped portions 14 of the front frame 10 in the manner illustrated in Fig. 4. This arrangement provides a very efficient construction tending to eliminate separation of the members at the joints due to twists and stresses, and, additionally, is much more economical in construction due to the fact that less material is required to form the connection.

Integral with the front frame 10 and upon the inner side thereof are a plurality of rearwardly extending lugs 18 spaced around the channel shaped portions 14 and adjacent thereto. These lugs 18 are adapted to support L-shaped clamping members 19, as clearly shown in Fig. 5, having their free ends extending outwardly into engagement with the free edges of the Z-shaped por-

tions 17 of the side panels 16. The clamping members 14 are provided with elongated transverse openings 20 to permit the clamping members 19 to be adjusted so as to forcibly engage the Z-shaped portions 17 of the side panels 16 and force the same into rigid cooperation with the channel shaped portion 14 of the front frame 10. The clamping members 19 are maintained in proper position and in engagement with the Z-shaped portions 17 by bolts 21, as clearly shown in Fig. 4. It will be noted that the free ends of the clamping members 19 are disposed within the grooves 15 as well as the free edges of the Z-shaped portions 17 of the side panels 16.

The top plate 22 is connected to the upper transversely extending channel portion 14 in the same manner as that just described and further explanation is deemed unnecessary. The top plate 22 and the side panels 16 are also connected together within the stove structure by providing inwardly extending flanges 23 upon the opposite sides thereof extending parallel with the main portion of the top plate 22, as shown in Fig. 3, while the upper ends of the side panels 16 are also bent inwardly to provide flanges 24 so as to engage the flanges 23, the side panels being secured together by the bolts 25.

In Fig. 6 a modification of the clamping means is illustrated, in which the side panels 16 and the front frame 10 cooperate in the same manner as previously described, but the clamping members 19, in this instance, are provided with flanges 26 adapted to extend over the lugs 18 and are connected to the lugs by bolts 27. In Fig. 7 a still further modification of the connection is illustrated, in which the clamping members 19 are secured to the lugs 18 by the bolts 21 in the same manner as that illustrated in Fig. 4, but the extended ends or free ends are adapted to engage with the upper portions of the Z-shaped portions of the side panels 16 to thereby rigidly hold the side panels and channel shaped portions 14 in cooperative engagement.

The bottom plate 28 may be connected, if desired, in the same manner as the top plate 22, as clearly shown in Fig. 2. However, this is not essential, in that the customary manner of connecting the bottom plate to the side panels 16 may be employed.

With the construction illustrated the outer walls of the stove present a smooth surface which is pleasing in appearance and at the same time eliminates the possibility of any damage being caused to the outer enameled surfaces by forming the connections and securing means entirely within the stove structure.

While I have described the preferred embodiment of the invention it is to be un-

derstood that I am not to be limited thereto, inasmuch as changes and modifications may be resorted to without departing from the spirit of the invention as defined in the appended claims.

Having thus described my invention, I claim:

1. In a stove construction, a frame provided with a channel-shaped portion, lugs on said frame, a panel having a portion adapted to engage said channel-shaped portion, and means attached to said lugs and adapted to engage said panel to thereby exert a pressure longitudinally thereof to retain said panel portion in engagement with said channel-shaped portion.

2. In a stove construction, a front frame provided with channel-shaped portions adjacent the top and sides thereof, side panels and top plate provided with offset portions adapted to engage said channel-shaped portions, and clamping means inside said panels and top plate and adapted to exert a pressure longitudinally and laterally thereof to retain said panels and top plate within said channel-shaped portions.

3. In a stove construction, a front frame having channel-shaped portions adjacent its edges, side panels provided with offset portions adapted to cooperate with said portions, and clamping members engageable with said offset portions to thereby prevent relative longitudinal separation between said panels and portions.

4. In a stove construction, a front frame having rearwardly extending channel-shaped portions adjacent the sides and top thereof, lugs spaced along said portions adjacent the inner edges thereof, panels and top plate provided with offset portions adapted to cooperate with said channel-shaped portions, means for clamping said offset portions at intervals to thereby exert a longitudinal pressure on said side panels and top plate for retaining the latter within said grooves, and means connecting the top plate and side panels from the inside thereof.

5. In a stove construction, a frame, a channel-shaped portion adjacent the outer portion of said frame, a panel having an offset edge cooperating with the upstanding leg and web of said channel-shaped portion, and means engaging said offset portion to maintain the latter in engagement with said channel-shaped portion.

6. In a stove construction, a frame, a channel-shaped portion adjacent the outer portion of said frame, a panel in alignment with the free leg of said channel-shaped portion and having an edge offset complementary to the contour between the free leg and web of said channel-shaped portion, and means carried by the frame and engageable with said offset edge for maintaining the latter

in engagement with said channel-shaped portion.

7. In a stove construction, a frame extending in one plane, a channel-shaped portion adjacent the outer portion of said frame, a panel extending in a plane at substantially right angles to the plane of said frame and having an offset edge cooperating with the free leg and web of said channel-shaped portion, and means carried by said frame and engageable with said offset edge to maintain the latter in engagement with said channel-shaped portion.

8. In a stove construction, a frame extending in one plane, a channel-shaped portion adjacent the outer portion of said frame, a panel extending in a plane at substantially right angles to the plane of said frame and having an offset edge cooperating with the free leg and web of said channel-shaped portion, and means carried by said frame within the angle formed by said frame and panel and engageable with the offset edge to maintain the latter in engagement with said channel-shaped portion.

In testimony whereof, I hereunto affix my signature.

EMMETT F. KENNEDY.
